UNITED STATES PATENT OFFICE.

CHARLES HENRY AUGUSTUS FREDERICK LOCKHART ROSS, OF BALNAGOWN CASTLE,
COUNTY OF ROSS, SCOTLAND.

PROCESS OF MAKING METAL-CLAD BULLETS.

1,059,212.

Specification of Letters Patent. Patented Apr. 15, 1913.

Application filed January 9, 1912. Serial No. 670,346.

To all whom it may concern:

Be it known that I, CHARLES HENRY AUGUSTUS FREDERICK LOCKHART ROSS, a subject of the King of England, residing at 5 Balnagown Castle, county of Ross, Scotland, have invented certain new and useful Improvements in Processes of Making Metal-Clad Bullets; and I do hereby declare the following to be a full, clear, and exact description of the invention, such as will enable others skilled in the art to which it appertains to make and use the same.

This invention relates to a process of making metal clad bullets or projectiles, and has 15 for its object to substantially or completely inclose the core of such bullets at both ends, while providing an accurate exterior contour, and a solid core or an interior cavity, as may be desired.

20 With these and other objects in view, the invention consists in the novel steps and combinations of steps constituting my process more fully hereinafter disclosed and particularly pointed out in the claims.

25 Referring to the accompanying drawings forming a part of this specification in which like numerals designate like parts in all the views:—Figure 1 is a diagrammatic sectional view illustrating one of the steps of

30 drawing the outer casing or jacket of my bullet; Fig. 2 is a view similar to Fig. 1, illustrating the step of forcing the metal core into the jacket shown in Fig. 1, and at the same time causing the bottom of said jacket

35 to assume a concaved shape; Figs. 3, 4, 5, 6 and 7 are diagrammatic sectional views illustrating various steps employed in closing the open end portion of the jacket by swaging operations, when the core is to

40 completely fill the jacket; Figs. 8, 9, 10, 11 and 12 are views similar to Figs. 3 to 7, illustrating like steps when the core is to only partially fill the jacket in the completed bullet; Fig. 13 is a diagrammatic sectional view of a portion of a swaging machine suitable for carrying out the foregoing

45 swaging steps; Fig. 14 is an elevational view partly in section of a finished bullet wherein the core completely fills the jacket; and, Fig. 50 15 is a view similar to Fig. 14, wherein the core only partially fills the jacket.

In carrying out my invention, I first force the jacket 1 by means of a plunger 2, through suitable dies 3, to draw the same to 55 the required dimensions, whereupon the core

4 is forced into the said jacket 1 by means of a suitable plunger, and at the same time, the shaping die 5 is caused to form the concavity 6 in the bottom of the jacket 1. The open end portion of the jacket is next subjected to a series of swaging operations by means of the hammers 7, as illustrated in Figs. 3 to 7, until the open end portion is substantially or completely closed. Any suitable swaging machine may be employed for this purpose, and in Fig. 13 I have illustrated a well known form in which the power is transmitted through the pulley 8, and the shaft 9, to the hammers 7, and in which the said hammers are caused to rapidly revolve past the rollers 10, which cause the said hammers to rapidly reciprocate and deliver blows in quick succession to the said open end of the jacket 1. The said hammers are further so shaped as to produce the desired 75 contour on the tapered end 11 of the finished bullet shown in Fig. 14.

When it is desired to produce a bullet of high penetrative power for military purposes, the lead core 4 is chosen of such dimensions that it will completely fill the jacket 1 in the finished bullet, and these dimensions may be suitably determined as follows:—A piece of lead of about the dimensions dictated by calculation is chosen, and a bullet is made therewith. The finished bullet is then cut open and the quantities of lead in the subsequent bullets made are increased or diminished according to the knowledge gained by the examination thus 80 made. When the exact quantity of lead required to fill the jacket is finally determined, it is noted, and all the bullets made thereafter will be found to be completely 85 filled. Of course, other methods may be employed for determining the proper quantities of lead, but the above empirical method is found to be expeditious and entirely satisfactory.

Supposing the upper end of the quantity of lead necessary to make the bullet shown in Fig. 14, extends to the line *a*—*b*, Fig. 2, then should it be desired to make a bullet with a cavity 13, such as is illustrated in Fig. 15, it is only necessary to permit the upper end of the lead to extend to say the line *c*—*d* in Fig. 2. Should it be desired to decrease or increase the cavity 13 in Fig. 15, then it is only necessary to raise or lower the upper end of the filling 4 in Fig. 2.

In other words, it is evident that by regulating the quantity of lead employed, the cavities 13 may be of any desired size, and therefore the bullet may be given any desired 5 qualities of expansion upon impact.

When expanding bullets are to be made, by my process, and the quantity of lead to be employed has been determined, then the jacket 1 is substantially or completely closed 10 by the series of swaging steps illustrated in Figs. 8 to 12 and the finished bullet will appear substantially as illustrated in Fig. 15. In fact, so complete is the control of the amount of lead in my bullet, that I may 15 use any quantity of lead from that necessary to completely fill the jacket to the smallest quantity, or even none at all, during the swaging process. In other words, I can produce a hollow bullet by my method completely closed at each end and containing no 20 filling at all.

The concavity 6 provided in my bullets are not absolutely essential, but are very 25 useful in permitting the powder gases to slightly expand the base of the bullet and thereby cause a more accurate fit with the rifling.

A bullet or projectile made in accordance 30 with my process possesses the important advantage of being closed at both ends. Heretofore processes for making bullets of this character have required that at least one end 35 of the bullet be left open in order to insert the filling material. It resulted from this 40 that if the base of the bullet was left open, the pressure of the powder gases, which is about fifteen tons or higher to the square 45 inch, coming upon the filling material 4 was liable to force said material through the pointed end of the casing 1, while the bullet was still in the rifling, and thereupon cause what is technically known as stripping. In order to avoid this, it has been necessary to make the point of the bullet 50 stronger than is necessary in my invention, and it has also been usual to turn-in the rim of the base of the casing to further strengthen the jacket. On the other hand, when the point of the bullet was left open,

then it was essential to cause the base of the 50 jacket to completely cover the filling, for otherwise the filling 4 would be forced through the jacket and cause stripping almost every time high powered bullets were fired. Bullets open at their pointed end, 55 however, invariably expand upon impact and are therefore not permitted for military uses. Further, they are not as accurate as are the closed end expanding bullets made in accordance with my invention and 60 illustrated in Fig. 15.

From the foregoing it will be clear that my process affords a ready and convenient means of making a bullet partially or completely closed at both ends, and also of making 65 a military, or an expanding bullet for sporting purposes, at will.

It is obvious that those skilled in the art may vary the steps above disclosed without departing from the spirit of my invention, and therefore I do not wish to be limited to said disclosure except as may be required by the claims.

What I claim is:

1. The process of making bullets, which 75 consists in suitably drawing to the required body dimensions of the bullet a tube having one end closed; and by successive hammer blows suitably shaping and closing the other end of said tube to complete the outer contour 80 of said bullet, substantially as described.

2. The process of making bullets, which 85 consists in suitably drawing to the required body dimensions of the bullet a tube having one end closed; placing a predetermined quantity of a filling material in said tube; and by successive hammer blows suitably shaping and closing the other end of said tube to complete the outer contour of said 90 bullet, substantially as described.

In testimony whereof, I affix my signature, in presence of two witnesses.

CHARLES HENRY AUGUSTUS
FREDERICK LOCKHART ROSS.
